KICK STAND CLAMP FOR BICYCLES

Ruben L. Pawsat, Maysville, Ky.

Application May 6, 1949, Serial No. 2,476

Term of patent 14 years

(CL. D90—18)

To all whom it may concern:

Be it known that I, Ruben L. Pawsat, a citizen of the United States, residing at 317 Main Street, Maysville, Mason County, State of Kentucky, have invented a new, original, and ornamental Design for Kick Stand Clamp for Bicycles, of which the following is a specification, reference being had to the accompanying drawings, forming part thereof. In the drawings,

Figure 1 is an end view of the kick stand clamp for bicycles, showing my new design;

Figures 2 and 3 are views in elevation of the respective sides of the clamp shown in Figure 1;

Figure 4 is a top plan view of the clamp; and

Figure 5 is a view in section taken on line V—V of Figure 2.

I claim:

The ornamental design for a kick stand clamp for bicycles, as shown.

RUBEN L. PAWSAT.
